UNITED STATES PATENT OFFICE.

WILLIAM A. PRESTON, OF FORT BRANCH, INDIANA.

GATE.

SPECIFICATION forming part of Letters Patent No. 322,852, dated July 21, 1885.

Application filed July 22, 1884. (No model.)

To all whom it may concern:

Be it known that I, WILLIAM A. PRESTON, a citizen of the United States, residing at Fort Branch, in the county of Gibson and State of Indiana, have invented certain new and useful Improvements in Gates, of which the following is a specification, reference being had therein to the accompanying drawings.

10 My invention relates to certain improvements in gates, and is designed to provide a gate that shall easily be opened or shut, especially by persons on horseback or in carriages, obviating the necessity of "getting out 15 to open the gate." Furthermore, the device is durable and simple.

The annexed drawings, referred to in describing the construction and operation of the gate, show, in—

20 Figure 1, a perspective view of the gate, with the rack-bar casing removed and shown separately; Fig. 2, a perspective view of the rack-bar and rope or cord attached, and Fig. 3 a section through the large or gate-operating 25 pulley.

The gate A has a main supporting-post, B, which is connected to a short post, C, by means of a bar or rail, D, supported also by a post, E, to which it is connected.

30 The gate is properly braced, and has two of its rails extended, as shown at F, the said extended rails operating above and below the bar D to support the said gate and to guide it, friction-rollers being provided at H in the 35 ends of the extended rails and at I on a portion of the supporting-post. These rollers serve to make the motion of the gate easy and smooth. One of the extended rails also projects from the front of the gate at K, and 40 when the gate is shut engages in the recess or slot L in the abutting post M, placed across the roadway from the supporting-post B. The post B is recessed at N for the reception of the large pulley O, having one end of its shaft 45 journaled in the post and the other in a guide, P, secured to the outside of the post and projecting outside the gate. The pulley-shaft has also on it a drum, R, and pinion S, set in a further recess, T, in the post B. Moving ver-

50 tically on the post, and adapted to engage with

the pinion, is a rack-bar, U, guided and protected by a casing, V, secured to the post, and having a projection, W, which in a measure protects the pulley. The rack-bar has on one side a grooved extension, X, in which the cord Y rests. This cord is connected to each end of the rack-bar, and takes a single turn around the drum R, causing the said drum, and also the pulley, to rotate as the said bar ascends or descends, the rack also engaging with the pinion and operating it at the same time. Were the cord alone used the tendency would be that it would slip on the drum, and were the rack used alone it would have a tendency to work hard or to cramp, the expense being too great to make them (the racks) as perfect as necessary to prevent the same; hence the two co-operate, the rack preventing the cord from slipping and the cord preventing the rack from cramping or working hard.

Connected both to the front and to the rear of the gate is the cord Z, which takes a turn around the pulley, and when that is turned forces the gate open or shut. Near the top of the standard is a cross-piece, A', to the ends 75 of which are pivoted the levers B' for operating the gate. The inner end of each lever is connected by a rod to the link on the end of the rack-bar.

In large gates, wire or chain is used in place 80 of cord or rope.

The gate is not necessarily six-bar, as shown, but may be of any height and work equally well.

A notch, C', is provided in the rear upper 85 end of the gate, in which rests one end of a lock-bar, D', the other end being secured to one of the levers B' near its inner end. The lock-bar has a guide, E', on the post B, and is operated to lock or unlock by the lever B'.

90 The broad idea or use of a rack-bar operated by extended levers and engaging with a pinion on the gate-operating shaft is not in itself claimed.

Having described the device, what I claim 95 is—

The combination, with a sliding gate, of a pinion, drum, and pulley on a shaft journaled in the gate-supporting post, a vertically-moving rack-bar having an extended 100

groove on one side, and a cord, wire, or chain connected to its ends, (the rack-bar and cord operating, respectively, on the pinion and drum,) and a cord, wire, or chain connected to the ends of the gate and passing around the pulley, substantially as and for the purpose specified.

In testimony whereof I affix my signature in presence of two witnesses.

WILLIAM A. PRESTON.
